UNITED STATES PATENT OFFICE

2,508,760

WINDOW SASH SUPPORT

Albert L. Judson, Handley, Tex.

Application January 16, 1947, Serial No. 722,411

2 Claims. (Cl. 292—74)

1

This invention relates to window construction and it has particular reference to sash control devices for frictionally retaining vertically operated sashes in adjusted positions in the frame, and its principal object resides in the provision of a structural sash design in which is embodied tensioned elements capable of frictional engagement with the window-jamb and operating in the sash channels on either side of the sash whereby the latter is supported at any desired position without the aid of such conventional devices as weights, bolts, and the like.

Another object of the invention resides in the provision of a sash construction embracing yieldable channel engaging elements by which the sash is secured against lateral movement in its channel and thus prevented from rattling or vibrating under the force of the wind, and by reason of the improved device, minimize the passage of drafts around the vertical sides of the sash.

A still further object of the invention is manifest in the provision of a sash structure which is especially adapted for installation in frames designed for masonry, and other types of structures, in which no provision has been made for weight wells, thus affording a desirable and practical sash control otherwise unattainable.

Broadly, the invention contemplates the provision of a sash construction of economical design suitable for use in all types of window installations embodying a dual, vertically adjustable sash arrangement, and obviates the necessity for unattractive conventional, and not too dependable, weight and cord assemblies.

While the foregoing objects are paramount, other and lesser objects will become manifest as the description proceeds, taken in connection with the appended drawings wherein:

Figure 1 illustrates the invention installed in longitudinal grooves in each stile of a window sash, portions shown broken away to reveal the grooves.

Figure 2 is a transverse sectional view of a window sash, taken on lines 2—2 of Figure 1, illustrating the invention in operation in the sash channels of the window frame.

Figure 3 is a fragmentary transverse sectional view of one stile showing the invention installed therein and in which a fibrous filler is employed.

Figure 4 illustrates the serpentine spring element in perspective.

Figure 5 is a fragmentary perspective illustration of one end of one of the tensioned shoes, and

2

Figure 6 is a fragmentary perspective illustration of one end of a modified form of the tensioned shoe.

The invention comprises, primarily, a shoe 10 of any suitable material, such as metal, plastic, or the like, formed with three sides and trough-like in transverse section, and preferably has its ends 11 at least partially closed by turning the extended portions 12 of its closed side 13 over the ends 11 and providing rounded surfaces 14 to facilitate the slidability of the members 10 in the sash channels 15 of a window frame 16.

The shoes 10 are vertically arranged in specially formed grooves 17 extending longitudinally of each stile 18 of a window sash 19 so that the closed sides or operative surfaces 13 of the members 10 are faced outwardly and engageable with the opposing surfaces 20 of the jambs 21 of the window frame 16 between the stops 22 which define the sash channels 15, as shown in Figures 1, 2 and 3.

The grooves 17 are closed at each end, as depicted in Figure 1, by routing the grooves so that a portion 23 of the stock remains thereby providing an elongated chamber, closed when the sash 19 is operatively installed in the frame 16, thus firmly embracing the shoes 10 in each of which a spring 24 is encased in the manner shown in Figures 1, 2 and 3.

The springs 24 are preferably of the leaf type and serpentine-like in longitudinal section, as illustrated in Figure 4, providing a bear at each of the arcs 25 on each face and at each end 26 which bears against the ends of the grooves 17 provided by the portions 23 of the stiles 18.

The springs 24 are arranged in the shoes 10 and bear outwardly thereagainst, with counter-pressure inwardly along the bottom of the grooves 17 whereby frictional associations are provided between the surfaces 13 of the shoes 10 and the jambs 21 of the frame 16, the rounded surfaces 14 on each end of the shoes 10 expediting the movement of the members along the sash channels 15. By this arrangement the sash 19 can be arrested in any desired position in the frame 16 without the use of weights and cords, or other conventional devices, an even tension being applied along the entire surface of each sash channel 15.

The invention may be modified, as shown in Figures 3 and 6, to include strips 27, of fibrous or yieldable materials, which are arranged in the shoes 28 of this structure to engage the surfaces of the jambs 21 in the sash channels 15 and function as weather strips to minimize the passage of drafts around the sash 19. Obviously, also, the

frictional association between these fibrous or rubber strips 27 and the jambs 21 is closer than that of the relatively smooth surfaces 13 of the shoes 10.

As illustrated particularly in Figures 3 and 6, each of the shoes 28 are formed with a channel 29 opposite the trough-like open side 30 of the structure by turning the sides 31 downwardly and then back upon themselves at *a*. The strips 27 are arranged in the channels 29 and, if desirable, 5 cemented in position. The springs 24 are arranged in the trough-like open side 30 of the members 28 in the same manner in which these elements are situated in the shoes 10.

The shoes 28 are also formed with a laterally projecting lug 32 at each end cut from the stock and turned outwardly and directed into the open side 30 providing stops or bearings for the ends 26 of the springs 24. The inwardly turned members 12 of the shoes 10 may also be utilized for the same purpose if desired, the ends 26 of the springs 24 being directed outwardly as opposed to the positions of these members as illustrated in Figure 1.

Manifestly, the structure herein shown and described is capable of considerable modification, by persons skilled in the art, without departing from the spirit and intent of the invention or the scope of the appended claims.

What is claimed is:

1. In a sash adjusting device and weather strip, for a window sash having a longitudinal groove formed in each stile thereof and slidably

vertically in a frame, a tensioned member arranged in each groove, the said members formed substantially H-shaped in transverse section providing opposing channels, a spring arranged in the innermost of said channels, and a weather strip disposed in the outer channels and engageable with said frame.

2. In a sash adjusting device and weather strip, for a window sash having a longitudinal groove formed in each stile thereof and slidably 15 vertically in a frame, a shoe member formed with a pair of opposing longitudinal channels and arranged in each of said grooves, a flat tensioning spring arranged in each of the inner channels and exerting tension on said shoe member outwardly, and a weather strip in each of said outer channels and engaging said frame under tension of said spring.

ALBERT L. JUDSON.
